COMBINATION GAS AND OIL BURNER

John S. Zink, Tulsa, Okla.

Application October 14, 1938, Serial No. 235,072

4 Claims. (Cl. 158—11)

This invention relates to improvements in burners and more particularly to a combination oil and gas burner capable of burning various types of gases without adjustment.

One of the objects of the invention is to provide a sectional burner to permit a plurality of gaseous fuels of different types to be simultaneously burned with the same burner structure.

Another object is to provide a sectional burner which will allow one section to be shut off in the event that the furnace becomes overheated.

Another object is to provide a burner which may be used for simultaneously burning oil and different types of gases or which may burn a plurality of types of different gases when the oil is shut off.

A further object is to supply a burner capable of burning all types of refinery gases without adjustment of the burner. It is designed to accommodate either natural or forced draft used with cold or preheated air.

An additional object is to furnish a combination oil and gas burner in which the gas burner is of sectional construction and so designed as to allow the oil burner to be adjusted relatively thereto whereby the head of the oil burner may be moved toward or away from the gas burner so that the secondary air can be properly admitted to the oil flame.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a horizontal sectional view of my improved burner partly in elevation.

Fig. 2 is an elevation of the outlet or discharge end of the same partly broken away and in section.

Fig. 3 is a similar view of the inlet end of the burner.

Fig. 4 is a fragmentary elevation partly in vertical section of a modification of the invention, and showing means for adjusting the door which controls the secondary air.

Fig. 5 is a front elevation of a modification of the gas burner head.

Fig. 6 is a similar view of another modification of said head.

Referring to the drawings, 7 designates a portion of a furnace wall having a doorway 8 which is partially lined by the metal wall frame 9 of my burner structure. The inlet end of the frame is flared as shown at 10 to facilitate the introduction of secondary air.

The frame, as best shown in Fig. 2, is provided internally with inwardly extending substantially

diametrically opposite ears 11 connected by bolts 12 to a spider 13 having a number of openings extending therethrough for the slidable support of a pair of gas tubes 14 and an oil tube 15. The discharge end portions of the gas tubes converge 5 toward one another as shown at 16, and merge into a sectional burner head 17. The latter, as best shown in Fig. 2, consists of hollow sections 18 and 19 which are provided with apertured ears 20, secured together by bolts 21 (Fig. 1). 10 Each section of the head is provided with a number of radiating arms 22, each of which preferably tapers toward its end and is provided with opposite walls 23 that converge toward the discharge end of the burner and are provided with 15 a series of apertures or ports 24. Due to this arrangement, gas issuing from confronting ports of each pair of arms will impinge in a position forwardly of the burner head.

Each of the sections of the head also has a 20 wall 25 extending diametrically across the burner head and provided at its medial portion with a semi-circular part 26. When the sections of the head are assembled, the parts 26 of the two sections are opposite one another and form a hole 25 or tube to accommodate the tube 15 which supplies oil to the oil burner head 28; the latter being positioned centrally of the gas burner head and being adjustable inwardly and outwardly so that the oil burner head 28 can be positioned 30 properly to receive secondary air which flows to the same between the spaces intermediate the arms 22.

As best shown in Fig. 1, the tubes 14 and 15 may be locked in any position of adjustment by 35 means of screws 29 which extend through portions of the spider 13 and impinge against the outer surfaces of the tubes.

Instead of making the gas burner head as in Figs. 1 and 2, it may be made as shown in Fig. 5 40 wherein each arm 30 of the burner has a single series of discharge ports 31 at one side thereof. As the ports are in the same side of each arm, obviously the gas discharged from the burner head 45 has a tendency to flow in a whirling manner, which is beneficial in the burning of certain gases.

Instead of using radiating arms for the gas burner head, I may employ parallel arms 32 as illustrated in Fig. 6. In that event each section of the gas burner head may be provided with one or more straight arms 32, one only being shown on each section 33 in Fig. 6.

The inlet end portion of each of the tubes 14 terminates in an aspirator funnel 34 provided with 55 a spider 35 which supports a dome shaped gas inlet element 36 having a discharge port 37. Gas is supplied to each of the elements 36 by a pipe 38 on which a disc 39 is adjustably arranged. The funnels admit primary air and the amount 60

admitted can, of course, be adjusted by the registered discs 38.

Oil is introduced into the tube 15 through a nipple 40 and it may be burned in conjunction with steam which is introduced into the tube 15 through a pipe 41, both of these parts being arranged, of course, at the inlet end of the tube 15.

The mouth 10 which admits the secondary air (in natural draft) is controlled by a register plate 42 that is slidably mounted on the tubes 14 and 15, and such plate is preferably provided with a lining plate 43 that has projections 44 which contact with the plate 42 for holding the main portions of these plates in spaced relation whereby some of the secondary air may pass through such space and dissipate the heat. Bolts 45 pass through the projections 44 and through the plates and hold the latter in assembled relation.

In the event that the burner is used with a forced draft, a plate 46 (Fig. 4) receives the gas tubes 14a and the oil tube 15a, and is secured at 47 to the outer wall 48 of the furnace, such wall being spaced from the inner wall 49 of the furnace whereby the forced air used for draft purposes will be conveyed into the wall frame 9a.

To provide for regulation of the secondary air, a plate 42a is arranged between the plate 46 and the mouth of the wall frame and is mounted to facilitate its movement toward and away from said mouth. The register door or plate 42a has projections 44a extending toward the plate 46, and each projection is secured to the inlet end portion of a supporting rod 49a. The rods are slidably supported by sleeves 50 integral with the plate 46 and each rod is provided at its outer end with a handle 51. Obviously the operator uses such handles in moving the plate 42a toward or away from the frame 9a.

In operation, one kind of combustible gas may be fed to one of the sections of the gas burner head, and another kind of combustible gas to the other one, and at such time oil may be supplied by means of the head 28 and, of course, during burning of such fuels the head 28 may be axially adjusted or if desired can be entirely removed from the assembly.

Referring now to the advantages of the invention, the following may be noted.

Where large combination gas and oil burners are required, my improved burner meets the requirements of the refining industry as it is a pre-mix type using both primary and secondary air. As each section of the gas burner has its own aspirator formed partially by the funnel 34, it will aspirate approximately 27% of the air with the gas and mix it before it is passed through the radiating arms of the burner head. Each aspirator has one large gas orifice or port 37 which is free from plugging even when used on wet or dirty gases. Each aspirator has its own air door 39 which permits the control of the primary air.

All types of refinery gases may be burned without adjustment of the burner, and of course, the structure is designed for either natural or forced draft and no additional parts are required for an installation using a wind box, as in that event, the bolts 45, shown in Fig. 1, may be replaced by the rods 49a shown in Fig. 4, and the plate 42, shown in Fig. 1, might be apertured to receive the bolts 47 shown in Fig. 4, which bolts are used in securing the supporting plate to the front wall of the furnace.

The herein described and illustrated embodiments of the invention have given satisfactory results and it will be apparent to those skilled in the art, after an understanding of the invention, that other changes and modifications may be made without departing from the spirit of and scope of the invention, and it is intended that all matters contained in the above description or shown in the drawings shall be interpreted as illustrative and not in a limiting sense.

What I claim and desire to secure by Letters Patent is:

1. In a structure of the character described, a wall frame, a spider secured to and extending across said frame, an oil tube extending through the medial portion of said spider and provided at its outlet end with an oil burner head, gas-conveying tubes extending through the spider at opposite sides of the oil tube and terminating at their outlet end portions in extensions which converge toward said oil burner head, a sectional gas burner head surrounding said oil tube and having sections connected to said extensions of the gas-conveying tubes, and means detachably connecting the sections of the gas burner head together.

2. In a structure of the character described, a wall frame, a spider secured to and extending across said frame, an oil tube extending through the medial portion of said spider and provided at its outlet end with an oil burner head, gas-conveying tubes extending through the spider at opposite sides of the oil tube and terminating at their outlet end portions in extensions which converge toward said oil burner head, a sectional gas burner head surrounding said oil tube and having sections connected to said extensions of the gas-conveying tubes, and means detachably connecting the sections of the gas burner head together, said oil tube being axially adjustable relatively to said gas burner head whereby the oil burner head may be moved toward or away from the gas burner head.

3. In a structure of the character described, a wall frame, a spider secured to and extending across said frame, an oil tube extending through the medial portion of said spider and provided at its outlet end with an oil burner head, gas-conveying tubes extending through the spider at opposite sides of the oil tube, and a sectional gas burner head surrounding said oil burner tube and having sections connected to the outlet end portions of the gas-conveying tubes, said oil tube and oil burner head being axially adjustable through the central portion of said gas burner head.

4. In a structure of the character described, a wall frame, a spider secured to and extending across said frame, an oil tube extending through the medial portion of said spider and provided at its outlet end with an oil burner head, said tube being axially adjustable in the spider, means for securing the tube to the spider, gas-conveying tubes extending through the spider at opposite sides of the oil tube, each gas-conveying tube being axially adjustable in the spider, means for securing the gas-conveying tubes to the spider, and a sectional gas burner head surrounding said oil tube and having sections connected to the outlet ends of the gas-conveying tubes, said gas burner head having a centrally disposed aperture in which the oil tube and oil burner head are axially adjustable.

JOHN S. ZINK.
